DOOR LATCH WITH ROTATABLE BOLT
Charles H. Lee, Taylor, Mich., assignor to General Motors Corporation, Detroit, Mich., a corporation of Delaware

Filed Apr. 20, 1960, Ser. No. 23,558
4 Claims. (Cl. 292—280)

This invention relates to a door latch, and more particularly to a rotatable bolt door latch for an automobile.

One feature of the invention is that it provides an improved door latch. Another feature of the invention is that it provides an automobile door latch having a novel construction and arrangement of the outside latch actuating means and locking means. A further feature of the invention is that the door latch includes an outside push button actuating lever which, in addition to its normal function as an unlatching lever, also serves as an intermittent or locking lever. Still a further feature of the invention is that the latch includes an outside push button actuating lever which is mounted for movement in two planes which are transverse to each other; yet another feature of the invention is that the outside push button actuating lever is mounted on the latch frame for swinging movement in a first plane wherein the lever is adapted to swing the detent out of engagement with the latching means, and in a second plane transverse to the first plane wherein said lever is uncoupled from the detent to lock the door, the mounting means for the push button lever including a pivot lever swingably mounted on the frame coaxially with the detent of the latch, and the push button lever being mounted on the pivot lever for swinging movement about an axis transverse to the axis of the pivot lever; and another feature of the invention is that it provides a novel arrangement of the undogging lever of the latch.

Other features and advantages of the invention will be apparent from the following specification and drawings, in which:

FIGURE 1 is fragmentary side elevational view of an automobile having the improved latch mounted in the front door;

FIGURE 2 is an enlarged section taken through a portion of the automobile door inside the door outer panel showing the latch in side elevation with the parts in unlocked position;

FIGURE 3 is a view similar to a portion of FIGURE 2 showing the parts in locked position;

FIGURE 4 is an enlarged vertical transverse section through a portion of the automobile door taken along the line 4—4 of FIGURE 1;

FIGURE 5 is a detail section taken along the line 5—5 of FIGURE 2; and

FIGURE 6 is a detail section taken along the line 6—6 of FIGURE 3.

Most modern automobiles are provided with door latches in which locking is accomplished by uncoupling two members of the latch so that, with the parts in locked position, the outside push button merely "free wheels" when actuated. It is often considered preferable to provide a latch with this free wheeling type of operation rather than a blocking type of operation in order to prevent the latch from being damaged should a lever or other tool be used to exert excessive force on the outside push button in an unauthorized attempt to open the door.

Free wheeling type latches are not per se and have been used for many years in many of the automobiles manufactured by the assignee of his application. In known latches of this type there is usually a link member, the function of which is to couple the outside actuating means to the detent which holds the bolt against rotation.

2

When the door is unlocked and the outside push button is actuated, the force exerted on the push button is transmitted through a chain of latch parts including this so-called intermittent link to move the detent out of holding engagement with the bolt. Since the bolt is now freely rotatable the door may be opened. In order to lock the door, the intermittent link is moved out of coupled relation with the detent so that the outside push button and the latch parts to which it is connected merely free wheel when the push button is depressed.

In the latch disclosed and claimed in this application there is no separate intermittent link. Instead, the push button lever upon which the outside push button operates is mounted for movement in two planes. When swung in a first plane upon depression of the outside push button, the push button lever swings the detent out of holding engagement with the bolt; but when swung in a second plane transverse to said first plane, the push button lever is uncoupled from the detent so that it free wheels when the push button is depressed. The novel construction through which this arrangement is achieved includes a pivot lever which is swingably mounted on the frame, preferably coaxially with the detent, and the push button lever is mounted on the pivot lever for swinging movement about an axis parallel to the axis of the pivot lever. The construction above described also permits use of a novel undogging lever arrangement, the function of which is to shift the latch parts from locked position to unlocked position whenever the detent is moved to release the bolt. This occurs when the door is locked against outside operation but is opened from the inside, and it also occurs when the door is locked while it is open and subsequently is closed unless the operator makes a conscious effort to override the undogging operation and locks the door without a key.

Referring now more particularly to the drawings, the reference character 10 designates an automobile having a body 12, a front door 14, a body center pillar 16 and a rear door 18. The door latch which is the subject of this invention is mounted in the front door 14 and is designated generally as 20. The front door 14, which is hingedly mounted at its front edge in conventional manner (not shown) on the automobile body, mounts the latch 20 on its rear jamb face so that the latch bolt will engage a conventional striker (now shown) which is mounted on the center body pillar 16. A suitable striker and the manner in which it engages the latch bolt are shown and described in detail in the patents to Cockburn et al. 2,871,049 and Van Voorhees 2,835,526, to which reference may be had if desired.

In order to open the door from outside the automobile, there is a gripping handle 22 which is fixedly mounted on the outer panel of the door and which carries a slideable push button assembly including a push button 24 and a push rod 26. The door may be locked from outside the automobile by a conventional key cylinder device 28. In order to open the door from inside the automobile, there is a conventional turn handle 30 mounted on the inner panel of the door at a location remote from the door latch and connected to the latch by a remote rod 32. Locking is accomplished from the inside through a garnish molding button 34 which is connected to the door latch through a chain of operating elements including a bell crank 36 mounted inside the door, a rod 38 extending from the bell crank 36 to a second bell crank 40, and a rod 42 extending from the bell crank 40 to the latch.

The latch 20, which is shown in detail in FIGURES 2—6, includes a frame having a body portion 44a which lies against the inner surface of the jamb face of the door 14 and is secured thereto by a plurality of bolts

46. A right angular flange portion of the frame 44b lies parallel to the inner panel of the door.

The latching means for holding the door closed includes a toothed gear type bolt 48 (FIGURE 4) which is rotatably mounted in a bolt housing frame extension 44c (FIGURE 2) on a bolt shaft 50 rotatably journaled between the outer wall of the bolt housing 44c and a frame extension 44d. The bolt 48 is rigidly mounted on the shaft 50, and adjacent the inner surface of the frame body 44a there is a toothed ratchet member 52 which also is rigidly mounted on the shaft 50 so that the bolt 48 and ratchet 52, which comprises the latching means, are in effect integral.

The latching means is held against rotation in a door-opening direction by a detent designated generally as 54 which is pivotally mounted on the flange portion 44b of the latch frame by means of a mounting stud 56. As shown in FIGURE 4, the detent has a foot 58 which normally engages the ratchet 52 to hold the latching means against rotation in a door-opening direction. The detent 54 has an arm 60 which extends inwardly from the pivot stud 56 for engagement by an inside actuator or remote control lever, later to be described, and an up-standing arm 62 of the detent projects upwardly from the pivot stud 56 and terminates in a right angle flange 64.

A pivot lever designated generally as 66 is swingably mounted on the stud 56 which, as shown in FIGURE 5, extends across the latch frame and has one end journaled in a bent bracket portion 44f of the frame. The pivot lever 66 is U-shaped in transverse section, having walls 66a and 66b which are journaled on the stud 56 and which are joined by a web portion 66c from which a lateral arm 66d projects. A spring 68 is connected between the arm 66d and the frame to bias the pivot lever in a counterclockwise direction as the parts appear in FIGURE 4, urging the upper end of the lever outwardly. A push button lever 70 is pivoted on the web portion 66c of the pivot lever by means of a rivet 72, the axis of which is transverse to the axis of the stud 56, and an overcenter spring 74 is connected between the pivot lever 66 and a push button lever 70 to yieldably hold the push button lever in an unlocked or locked position, as selected, relative to the pivot lever. FIGURE 2 shows the unlocked position of the parts and FIGURE 3 shows the locked position thereof.

Near its upper end the push button lever 70 is formed at one side with a pickup flange 76. With the parts in unlocked position the flange 64 of the detent lies in the path of swinging movement of the pickup tab 76 when the pivot lever and push button lever are swung upon depression of the push button 24. However, when the push button lever is shifted relative to the pivot lever to the locked position of FIGURE 3, the flange 64 is out of the path of swinging movement of the pickup tab 76, and upon depression of the push button 24 the push button lever 70 merely free wheels and does not move the detent.

The construction above described eliminates a separate intermittent link device which has been conventionally used in vehicle door latches wherein parts are uncoupled in order to lock the door. The push button lever is mounted on the pivot lever to swing relative to the pivot lever in a plane parallel with the axis of pivotal mounting of the pivot lever, and therefore is swingable in either of two planes which extend transversely relative to each other.

The push button lever may be shifted between its unlocked and locked positions by means of the garnish molding button 34 which, when depressed, pulls on the rod 42 and shifts the push button lever relative to the pivot lever from the unlocked position of FIGURE 2 to the locked position of FIGURE 3. From the outside of the automobile, turning a proper key in the conventional key cylinder 28 will also shift the push button lever since the pawl of the key cylinder enters a slot 78 in the push button lever. Pulling up on the garnish molding button or turn-

ing the key in the opposite direction will, of course, shift the push button lever back to its unlocked position.

The remote connecting rod 32 is connected to the lower end of a remote lever 80 which is pivotally mounted on the frame at 82. The remote lever is formed as a bell crank, having an arm 84 which overlies the detent arm 60 so that when the remote handle 30 is turned to pull on the rod 32 and swing the remote lever in a counterclockwise direction as the parts appear in FIGURES 2 and 3, the arm 84 in its downward movement will pick up the detent arm 60 and move the detent foot 58 out of engagement with the ratchet 52.

The door latch includes the features of remote undogging, automatic undogging and keyless locking. By the term "remote undogging" it is meant that when the latch is locked against outside operation and is opened from the inside the latch parts will be shifted to unlocked position. By the term "automatic undogging" it is meant that if the latch is locked while the door is open, slamming the door will shift the parts back to unlocked position. However, if the operator so desires he may accomplish keyless locking by a conscious operation while the door is being closed.

The undogging functions are achieved through movement of the detent which swings when the door is opened from the inside and which also swings whenever the door is slammed shut. When the door is closed the teeth of the bolt 48 ride over complementary teeth of the striker in the manner disclosed in Patents 2,871,049 and 2,835,526, the detent foot camming over the sloping back-side of the teeth of the ratchet 52. An undogging lever 86 is pivotally mounted intermediate its ends on a stud 88 which projects from a mounting bracket 90 that is bent from the latch frame. One arm 92 of the undogging lever 86 is formed with a bent pickup tab 94 which, as shown best in FIGURE 6, abuts the inner side of the flange 64 on the detent. The other arm of the undogging lever 86 is formed as a hook having an undogging end 96 which lies adjacent the edge of the push button lever 70 at a location above the pivot stud 72. Whenever the detent swings, it picks up the undogging lever and causes it to swing in a clockwise direction as the parts appear in FIGURE 6 so that the undogging surface 96 will kick the push button lever 70 to unlocked position in the event the lever is located in locked position at this time. A spring 98 which is coiled around the stud 88 has one end hooked into the frame bracket 90 and the other end bearing against the pickup tab 94 on the undogging lever so that the spring 98 biases the undogging lever into constant engagement with the detent and also biases the detent to its normal latching position illustrated in FIGURE 4.

In the event the operator wishes to lock the door without a key, he can override the automatic undogging function when the door is closed by depressing the outside push button 24 to swing the pivot lever 66 and the push button lever 70 to a position where the push button lever is out of the path of movement of the undogging surface 96 of the undogging lever. With the parts in this position, the undogging lever merely free wheels when it is moved upon swing movement of the detent.

While I have shown and described one embodiment of my invention, it is capable of many modifications. Changes, therefore, in the construction and arrangement may be made without departing from the spirit and scope of the invention, as set forth in the appended claims.

I claim:

1. A door latch of the character described, including: a frame; latching means rotatably mounted on said frame, comprising a bolt and a ratchet member rigid with the bolt and rotatable therewith; a detent pivotally mounted on the frame and having a foot engageable with said ratchet for blocking rotation of the latching means in one direction; outside actuating means for swinging said detent foot out of engagement with said ratchet comprising a push button lever adapted to have direct engage-

ment with said detent and a push button operator adapted to have direct engagement with said lever; means for mounting said push button lever on said frame for swinging movement in a first plane between operative and operated positions and in a second plane transverse to said first plane between unlocked position wherein said lever is coupled to said detent and locked position wherein said lever is uncoupled from said detent, movement of said lever in said first plane from operative position to operated position causing movement of said detent when said lever is in unlocked position, said last mentioned means comprising a pivot lever pivotally mounted on said frame coaxially with said detent, the push button lever being mounted on said pivot lever for swinging movement relative to said pivot lever about an axis transverse to the axis of said pivot lever; inside actuating means comprising a lever pivotally mounted on the frame and movable to swing said detent foot out of engagement with said ratchet; and an undogging lever pivotally mounted on said frame and having a part lying in the path of swinging movement of said detent and another part lying adjacent said push button lever when said push button lever is in uncoupled position, said undogging lever swinging responsive to movement of said detent to cam the push button lever into coupled relation with the detent.

2. A door latch of the character described, including: a frame; latching means rotatably mounted on said frame, comprising a bolt and a ratchet member rigid with the bolt and rotatable therewith; a detent pivotally mounted on the frame and having a foot engageable with said ratchet for blocking rotation of the latching means in one direction; outside actuating means for swinging said detent foot out of engagement with said ratchet comprising a push button lever adapted to have direct engagement with said detent and a push button operator adapted to have direct engagement with said lever; means for mounting said push button lever on said frame for swinging movement in two planes that are transverse relative to each other, said mounting means comprising a pivot lever swingably

5

mounted on said frame, said push button lever being mounted on said pivot lever for pivotal movement relative to the pivot lever in a plane parallel to the axis of said pivot lever; and inside actuating means for moving said detent foot out of engagement with said ratchet.

3. Apparatus of the character claimed in claim 2, wherein said pivot lever is mounted on said frame coaxially with said detent.

4. A door latch of the character described, including: a frame; latching means rotatably mounted on said frame, comprising a bolt and a ratchet member rigid with the bolt and rotatable therewith; a detent pivotally mounted on the frame and having a foot engageable with said ratchet for blocking rotation of the latching means in one direction; outside actuating means for moving said detent foot out of engagement with said ratchet comprising a push button lever adapted to have direct engagement with said detent and a push button operator adapted to have engagement with said lever; and means for mounting said push button lever on said frame for swinging movement in a first plane between operative and operated positions and in a second plane transverse to said first plane between unlocked position wherein said lever is coupled to said detent and locked position wherein said lever is uncoupled from said detent, movement of said lever in said first plane from operative position to operated position causing movement of said detent when said lever is in unlocked position, said mounting means comprising a pivot lever swingably mounted on said frame coaxially with said detent, the push button lever being mounted on the pivot lever for swinging movement relative to said pivot lever about an axis transverse to the axis of said push button lever.
